CLAIM

I claim the ornamental design for a “tree-crown-shaped solar panel”, as shown as described.

DESCRIPTION

FIG. 1 discloses the front view of tree-crown-shaped solar-panel.

FIG. 2 discloses top view of tree-crown-shaped solar-panel; and,

FIG. 3 discloses side view of tree-crown-shaped solar-panel.

(Continued)

The broken lines and the plus(+) and minus(−) signs shown represent unclaimed subject matter and form no part of the claimed design.

1 Claim, 2 Drawing Sheets
